Filed Feb. 17, 1969, Ser. No. 15,819

Term of patent 14 years

Int. Cl. D30—02

U.S. Cl. D30—13

FIG. 1 is a perspective view from the top and side of a combination bird bath and feeder embodying my new design;

FIG. 2 is a front elevational view of the combination bird bath and feeder; and

FIG. 3 is a top plan view of the combination bird bath and feeder.

The right-hand and left-hand side elevations and the rear elevation of the combination bird bath and feeder are substantially identical to the front elevational view shown in FIG. 2.

I claim:

The ornamental design for a combination bird bath and feeder, substantially as shown and described.
